UNITED STATES PATENT OFFICE.

WILLIAM A. MARSHALL, OF LUDINGTON, MICHIGAN.

MACHINE FOR TRUING PULLEYS.

SPECIFICATION forming part of Letters Patent No. 627,862, dated June 27, 1899.

Application filed April 6, 1897. Serial No. 630,929. (No model.)

To all whom it may concern:

Be it known that I, WILLIAM A. MARSHALL, a citizen of the United States, residing at Ludington, in the county of Mason and State of Michigan, have invented certain new and useful Improvements in Machines for Truing Pulleys; and I do hereby declare the following to be a full, clear, and exact description of the invention, such as will enable others skilled in the art to which it appertains to make and use the same.

The object of this invention is to provide a machine for truing the peripheries or outer faces of large pulleys or wheels, and is especially adapted for truing the faces of band-saw wheels, being made in different sizes to suit the character of work or size of the wheels to be operated upon.

The invention contemplates a construction in which the device takes its driving power from the wheel which is being operated upon without removing said wheel from its shaft, and the arrangement of the parts is such that the emery or grinding wheel is susceptible of minute adjustment to bring it in proper contact with its work to act upon the entire surface of the periphery of the wheel.

Having the above objects in view, the invention consists in an apparatus or machine for truing or grinding the face of a pulley or wheel, comprising a supporting-frame carrying a shaft upon which the grinding-wheel is mounted, and a second shaft having a pulley or wheel in engagement with the wheel to be trued and geared to the shaft of the emery-wheel.

The invention further consists in a machine for truing or grinding the face of a pulley or wheel, comprising a supporting-frame having a shaft journaled thereon and carrying the emery-wheel, a second shaft having a pulley or wheel in engagement with the wheel which is being operated upon, and devices for adjusting the emery-wheel.

In the following specification I have entered into a detailed description of the parts which constitute the invention, reference being had to the accompanying drawings and to letters and numerals thereon, which designate the different parts, and what I consider to be the novel features of construction are specifically recited in the claims.

In the accompanying drawings, forming part of this specification, Figure 1 is a perspective view of a truing or grinding machine 55 constructed in accordance with my invention. Fig. 2 is a front view of the machine or apparatus. Fig. 3 is a transverse sectional view on the line 3 3 of Fig. 2, and Fig. 4 is a vertical sectional view through the longitudinal 60 center of the machine on the line 4 4 of Fig. 3.

With reference to said drawings, 1 designates a bed-plate upon which the machine is placed and firmly held, the said bed-plate for this purpose being provided with upwardly projecting side flanges, through which pass clamping-screws 2, that engage the machine and, being adjustable, permits said machine to be shifted or turned at an angle with respect to the bed-plate, for the purpose hereinafter set forth. Clamped in the bed-plate is a rectangular frame 3, which forms the supporting-frame of the machine and is constructed to present guides for the movable parts thereof. To this end the supporting-frame is made 75 up of side pieces 4, connected to each other at one end by a cross-piece 5, and upon this end of the frame and extending across the same are parallel guide-rails 6, having grooves 80 a, while the inner edges of the side pieces are provided with grooves b. Having a sliding movement between the guide-rails 6 is a bearing-box 7, forming a support for one end of the main shaft 8, upon which the grinding-wheel 9 is mounted, said box having lateral 85 flanges c fitting the grooves a. The main shaft has a longitudinal sliding movement in this bearing-box to provide for an adjustment of the shaft and grinding-wheel. The other end of the shaft is supported in a bearing-box 90 10, which latter has a sliding movement corresponding with that of the bearing-box 7 and is provided with lateral flanges or tongues d, fitting in grooves e, formed in the side pieces 11 of a frame 12, mounted in the supporting-frame. 95 In addition to the lateral movement which the box 10 has in the frame 12 said bearing-box is also provided a longitudinal movement, and to this end the frame 12, carrying the box, is adapted to slide between the side pieces of the supporting-frame and has lateral flanges or tongues f fitting the grooves b in said side pieces.

The shaft moves longitudinally with the box 10, the grinding-wheel 9 bearing

against one side of said box, while the rigid collar 35 bears against the other side, and when moved or adjusted longitudinally the shaft slides in the other box, which has only 5 a lateral movement on the supporting-frame.

The shaft 8 is driven from a shaft 15, journaled in the upper ends of inclined supports 16, hinged to one of the side pieces of the supporting-frame 3, and the said shaft has a friction-wheel 17 fixed on one end and adapted 10 to be brought into engagement with the periphery of the wheel which is being trued to receive power therefrom. A driving-belt 14 passes from a pulley 18 on shaft 15 over a pulley 13, loosely mounted on the main shaft, said 15 driving-belt being crossed between the pulleys in order that the grinding or emery wheel which is mounted upon the main shaft will be rotated in an opposite direction from the 20 rotation of the pulley or wheel upon which it acts. The wheel 17, which is the driving-wheel of the grinding-machine, is brought into engagement with the wheel or pulley upon 25 which the device is operating by swinging the inclined supports 16 and holding them in an adjusted position by means of the brace 19, it being understood that the wheel being operated upon is fast upon a driven shaft. In other words, the pulley or wheel to be ground 30 is not removed from its shaft, so that the power to drive the grinding or truing machine is taken from said driven shaft.

In order to provide for adjusting the grinding-wheel so as to bring it into proper contact 35 with the wheel or pulley which it is desired to true, the movable boxes for the shafts upon which said grinding-wheel is mounted are connected to certain devices for moving them with respect to the supporting-frame 3. For 40 this purpose a horizontal shaft 20 is provided, having a crank-handle 21 at one end and provided with bevel-wheels 22 and 23. This shaft is supported at one end in a bracket 24, secured to one of the side pieces 4 of the supporting-frame, and the other end of said shaft 45 is supported loosely in a bracket 25, carried by the sliding frame 12, which permits said frame to move independent of the shaft, the bevel-wheel 23 being loosely mounted upon 50 the said shaft and rotates therewith by means of the ordinary spline and feather. A shaft 26 is geared to the bevel-wheel 22 by means of a corresponding wheel 27 in mesh therewith, and the said shaft 26 has a threaded inner 55 end which engages a lug 28 on the bearing-box 7, provided with a threaded aperture for the purpose. A lug 29 is mounted upon the other bearing-box 10 and is engaged by a shaft 30, which bears in the bracket 25 of the sliding frame 12 and has a bevel-wheel 31 in mesh with the bevel-wheel 23, movable on the shaft 20. By this arrangement of shafts and intermeshing gear-wheels in connection with the threaded rods 26 and 30 the grinding- 60 wheel can be moved laterally of the machine to and from the periphery of the wheel to be operated upon by turning the shaft 20. Now

in order to provide for a longitudinal movement of the grinding-wheel means are provided for moving the sliding frame 12, which 70 carries one of the bearings for the shaft 8, upon which the said grinding-wheel is mounted, and to this end an operating shaft or screw 32 is passed through the bearing-box 7 and has a threaded end which engages a threaded 75 sleeve or socket 33, carried by the bearing-box 10.

It will be seen that by turning the crank-handle 34 at the end of the screw 32 the frame 12, which carries the bearing-box 10, will be 80 moved within the supporting-frame 3, and the main shaft being held upon this bearing-box by means of the grinding-wheel and rigid collar 35 will move therewith and carry the grinding-wheel across the periphery of the wheel 85 to be trued or ground. To provide for connecting the pulley 13 to the shaft 8, so that the latter can move freely through said pulley, the ordinary spline and feather are also employed at this point. 90

As hereinbefore stated, the frame 3, which forms the supporting-frame of the machine, is held within the bed-plate 1 by means of the set-screws 22, engaging the sides of said frame 3, and by properly adjusting these screws the 95 angle of said frame can be changed with respect to the bed-plate, and consequently the grinding-wheel adjusted with respect to the periphery of the wheel or pulley which is being operated upon. The bed-plate is also provided with outwardly-projecting lugs 35 on opposite sides, to which the inclined supports 16 are fastened, this particular arrangement of the bed-plate providing for changing the supports to provide a right or left hand machine or adapt the machine to accommodate the pulley or wheel which is to be trued or ground. 100

From the foregoing description, in connection with the accompanying drawings, the 110 construction and operation of my improved machine for grinding or truing the faces of large pulleys or wheels will be readily apparent, for the frame is supported adjoining the wheel or pulley to be trued, and said wheel 115 or pulley having a rotation with its shaft the wheel 17 of the machine is brought into contact therewith and, receiving rotation by frictional contact, will rotate the shaft 15, and through the intervention of the belt 14, that 120 is crossed, as shown, the shaft 8 will be rotated in an opposite direction from the rotation of the wheel or pulley to be ground or trued, so that the grinding-wheel fixed on said 125 shaft will better act upon the face of said wheel or pulley. When it is desired to adjust the grinding-wheel toward the periphery of the wheel or pulley, it can be done by turning the crank-handle 21, which will turn the threaded rods 26 and 30 through the intervention of the shaft 20 and bevel-wheels and slide the supports or bearings for the shaft of the emery-wheel to move the latter to the desired extent. A further adjustment can 130

be had to move the emery-wheel across the periphery of the wheel or pulley by turning the screw 34, which moves the sliding frame 12 and the bearing-box, which is connected directly to the shaft of the said grinding-wheel. Thus it will be seen that I provide a machine which takes its power from the pulley or wheel which is being trued or polished, and the emery or grinding wheel is supported in such manner as to make the same capable of various adjustments to bring it in proper contact with the surface to be operated upon.

Having thus described my invention, what I claim as new, and desire to secure by Letters Patent, is—

1. In a machine for the purpose set forth, the combination with a bed-plate, of a frame adjustable therein and carrying bearings which are movable with respect to the frame, a shaft journaled in the bearings and having an emery-wheel mounted thereon, means for adjusting the emery-wheel by moving the bearings of the shaft; together with the second shaft suitably supported and geared to the first-named shaft, and a roller or wheel on the second shaft adapted to be brought in contact with the pulley or wheel which is operated upon, substantially as shown and described.
2. In a machine of the character described, the combination with a frame having transverse guide-rails, bearings or shaft-supports in sliding engagement with said rails, the shaft supported in said bearings carrying an emery-wheel, means for moving the bearings or shaft-supports, and driving mechanism for the shaft, substantially as shown and described.
3. In a machine of the character described, the combination with the supporting-frame presenting transverse guide-rails, bearings or shaft-supports in sliding engagement with said rails, threaded rods engaging the bearings and in mesh with a shaft common to both, the movable shaft-supports carrying the shaft having an emery grinding-wheel mounted thereon, and means for turning the said shaft, substantially as shown and for the purpose set forth.
4. In a machine of the character described, the combination with the supporting-frame presenting transverse guide-rails at one end, a frame mounted within said supporting-frame and in sliding engagement therewith, guide-rails carried by the sliding frame, bearings or shaft-supports in sliding engagement with the guide-rails, threaded rods engaging the bearings or shaft-supports, and means for turning said threaded rods in unison; to-
- gether with the shaft carried by the movable bearings and having an emery-wheel, a second shaft suitably supported and geared to the shaft of the emery-wheel, and a roller or wheel on the second shaft adapted to be brought into engagement with the periphery of the wheel which is operated upon, substantially as shown and for the purpose set forth.
5. In a machine of the character described, the combination, of the supporting-frame having longitudinal and transverse guide-rails, a frame movable within the longitudinal guide-rails and provided with transverse guide-rails, bearings or shaft-supports at each end of the frame in sliding engagement with the transverse guide-rails, a shaft mounted in the shaft-supports, said shaft being movable with the shaft-supports carried by the movable frame and slideable in the other shaft-supports, and a screw adapted to adjust the movable frame; together with a second shaft supported in suitable bearings, a pulley mounted thereon and connected by belt to a pulley on the main shaft, a friction-wheel on the second shaft adapted to be brought into engagement with the wheel being operated upon, and a grinding-wheel on the main shaft, substantially as shown and for the purpose set forth.
6. In a machine of the character described, the combination, of the supporting-frame having longitudinal and transverse guide-rails, a frame movable within the longitudinal guide-rails and provided with transverse guide-rails, bearings or shaft-supports at each end of the supporting-frame in sliding engagement with the transverse guide-rails, a shaft mounted in the shaft-supports and carrying a pulley and grinding-wheel, said shaft being movable with the movable frame and shaft-supports carried thereby and slideable in the other shaft-supports, and a screw adapted to adjust the movable frame; together with extensible bars hinged to the supporting-frame, a brace-rod connected to one of said bars, a second shaft mounted in the extensible bars, a pulley on said second shaft connected by a crossed belt with the pulley on the main shaft, and a friction-wheel on the second shaft adapted to be brought into engagement with the wheel being operated upon, substantially as shown and for the purpose set forth.

In testimony whereof I have signed this specification in the presence of two subscribing witnesses.

WM. A. MARSHALL.
